CLAIM

The ornamental design for a three panel undercounter light, as shown and described.

DESCRIPTION

FIG. 1 is a bottom perspective view of the three panel undercounter light according to my design;

FIG. 2 is a front view of my design;

FIG. 3 is a left side view of my design with the right side view being a mirror image thereof, minus the power switch;

FIG. 4 is a back view of my design;

FIG. 5 is a bottom view of my design; and,

FIG. 6 is a top view of my design.

The broken lines shown in FIG. 4 are for illustrative purposes only and form no part of the claimed design.
